UNITED STATES PATENT OFFICE

HERBERT G. OLIVER, OF MAMARONECK, NEW YORK

HAIRPIN CLIP

Application filed December 1, 1926. Serial No. 151,850.

This invention relates to a hair pin clip such as used in building constructions.

In building constructions, it is common practice to support the channel furring irons by the angle carrying bars, which, in turn, are supported by the toggle hangers which depend from the floor construction. These toggle hangers have portions which are embedded in the floor and extensions which de-

pend from the lower surface of the floor.

The angle carrying bars are attached to the toggle hangers by suitable means such as rivets and are for the purpose of carrying the channel furring irons which extend in angular relation to the angle carrying bars and relatively close together. This arrangement leaves a space between the channel furring irons and the lower surface of the floor. It has been the practice to secure the channel

furring irons to the angle carrying bars by hairpin clips which include bight portions adapted to embrace the channel furring irons and leg portions adapted to be bent over the upper edges of the angle carrying bars.

The application of these hairpin clips has been somewhat difficult in the past and it has been common practice to first slip a hairpin clip over the channel furring iron after the latter has been put in place against the lower ends of the angle carrying bars so that the bent ends or legs of the hairpin clip overlie the upper edge of the angle carrying bar. To bend these extended ends or legs downwardly to embrace the angle carrying bar and to

form, in effect, hooks over the upper edge of the same, a practice has been resorted to which included the placing of a small pipe over these ends or legs and bending them down as far as possible with the use of this pipe. To get the maximum action of this

pipe, it has been customary to bend the pipe at an angle so that it will contact with the channel furring irons or with the angle carrying bar only after the legs of the hairpin clip have been bent to a considerable extent. However, it has not been possible to bend these legs by means of this pipe into their final position and the practice has been, after the removal of the pipe, to complete the bending by striking the legs with a hammer.

The above practice has been attended by many disadvantages. The relatively small space between the floor and the channel furring irons affords an inconvenient working space and the result has been that the hammering down of the legs not only consumes a comparatively great amount of time, but does not insure the clinching of the hairpin clip on the angle carrying bar in such position that the channel furring irons will be held tightly and immovably against the angle carrying bars. There are many other disadvantages also incident to the use of the bending pipe and hammer.

In my copending application, Serial No. 125,259, filed July 27, 1926, I have illustrated a tool for applying the hairpin clips in such manner that all the above referred to disadvantages are overcome.

The present invention resides in the construction of a hairpin clip which is so formed that its application will be greatly facilitated.

The hairpin clips which are at present in commercial use, are so formed that after they are put in place with the bight portion embracing the channel furring iron and the leg portions engaging the upper edge of the carrying bar, the legs must be immediately bent over said upper edge in order to maintain the hairpin clip in place. The result is that each hairpin clip must not only be put in place but must be immediately clinched in place. Since this is true, it is impossible to first apply a series of hairpin clips and then clinch them. The present clip, however, is so formed that a series of the clips may be put in place and the entire series then clinched. This, of course, results in a great saving of time and incidentally of expense and results in an eminently more satisfactory job.

In the drawings:

Figure 1 is a fragmentary view showing the relation of the elements of the building construction and the position of the old type of hairpin clip before it has been clinched;

Figure 2 is a similar view showing the hairpin clip constructed in accordance with the present invention after it has been put in place but before it has been clinched;

Figure 3 is a similar view showing the hairpin clip of Figure 2 in its clinched condition;

Figure 4 is a view taken at right angles to Figure 3; and

Figure 5 is a perspective view of the hairpin clip constructed in accordance with this invention.

In the commercial art, a hairpin clip such as shown in Figure 1, is almost universally used. This clip, as will be seen, from the drawing, includes a body portion 1, and legs 3, which are bent angularly with respect to the bight portion, the bending being carried to only such extent that the legs form obtuse angles with the body portion. This bending of the legs has been to facilitate the application of the hairpins to a carrying bar after the bight portion has been engaged with the furring iron. After application the hairpin clips occupy substantially the position shown in Figure 1. However, it is quite impossible to place a series of clips in position before starting the clinching operation as the weight of the furring iron and the inclination of the legs of the hairpin clips result in the slipping of the hairpin clips on the upper edge of the carrying bars and consequently, result in their displacement. It has, therefore, been necessary as heretofore stated to first place a hairpin clip and then immediately clinch it before the next has been placed. The disadvantage of this is perfectly patent.

The clip constructed in accordance with the present invention, includes legs which are so formed that the clip can be snapped in place, the engagement of the legs with the upper edge of the carrying bars will be maintained and the furring irons held in place irrespective of any clinching operation. Therefore, a series of hairpin clips of this construction may be snapped in place to position the furring iron and after having been snapped in place in the furring position the successive clips of the series may be clinched.

The clip which is made preferably of wire includes a bight portion 1, which is adapted to engage the furring iron 2, and legs 3, which are adapted to be snapped over the upper edge of the carrying bar 4, which carrying bar is supported by toggles hanger 5, which depends from the floor of the building 6.

At the junction between the legs 3 and the bight portion 1 of the hairpin clip, the wire is bent to form seats 7 which are adapted to engage over the upper edge of the carrying bar. The distance between that portion of the hairpin, which is marked 8, when the furring iron is drawn tightly against the carrying bar and the portion of the legs, which is marked 9, adjacent to their junction with the seats 7, is less than the distance between the upper edge of the carrying bar and the lower edge of the furring iron. When the hairpin is pushed into position with the legs

overlying the upper edge of the carrying bar, the legs being resilient will yield to permit the forcing of the hairpin clip in place. When the hairpin clip reaches a position such that the upper edge of the carrying bar is aligned with the seats 7 of the clip these seats will snap over the said upper edge and the hairpin clip will be held in place, in turn maintaining the proper relation between the carrying bar and the furring iron.

This construction of hairpin clip not only facilitates the application of the clip by the old method which is hereinbefore described but also by the new method and by means of the new tool which I have described in my compeding application hereinbefore referred to.

It will be understood that the arms, 3, of the clip may be clinched into position either by forcing or hammering them down in place or by pulling or drawing them down as by a tool such as shown in my prior application referred to above. As the particular method or means resorted to do not form any part of this invention, no detailed description is presented and the invention is not confined in this respect.

While I have described a particular embodiment of my invention, it is to be understood that many modifications may be made within the spirit of the invention and without departing from the scope of the claims and I, furthermore, do not wish to be limited to the particular embodiment illustrated.

I claim:

1. A clip for supporting a member from another member comprising a bight portion for the accommodation of the first member and resilient leg portions adapted to be snapped over the second member, said leg portions extending angularly from the bight portion and having their free ends disposed at less vertical distances from the heel of the bight portion than the jointed ends to provide concave downward bends serving as seats between the free ends and jointed ends for disposition on the second member.

2. A clip of the class described comprising a substantially U-shaped member having the free ends of the legs offset angularly and disposed in spaced, substantially parallel relation, said legs being joined to the body of the U-shaped member in concave downward bends providing seats for disposition on a supporting member, said legs possessing resiliency for exerting a resilient grip on said supporting member when disposed thereon.

3. A clip for suspending one member from a second member comprising a unitary element having a portion for supporting the first member, a vertical portion extending from the supporting portion, and an oblique portion extending from the top of the vertical portion, said oblique portion being joined to the vertical portion in a concave downward

bend forming a seat for disposition of the clip on the second member, said oblique portion being adapted to be snapped over the second member to bring the seat thereon and to exert a resilient retaining grip on the second member in service.

In testimony whereof, I have signed my name to this specification.

HERBERT G. OLIVER.
